UNITED STATES PATENT OFFICE.

JOHN M. WHEELER, OF CADIZ, OHIO.

RAILWAY-TRACK CONSTRUCTION.

1,296,348.

Specification of Letters Patent.

Patented Mar. 4, 1919.

Application filed August 8, 1918. Serial No. 248,966.

To all whom it may concern:

Be it known that I, JOHN M. WHEELER, a citizen of the United States, residing at Cadiz, in the county of Harrison and State 5 of Ohio, have invented certain new and useful Improvements in Railway-Track Construction, of which the following is a specification.

This invention relates to an improved 10 railway track construction and has as its primary object to provide an arrangement wherein the track rails will be rigidly supported at their meeting ends to accordingly eliminate relative vertical movement of the 15 rail ends and consequent breaking of the rails.

The invention has as a further object to provide a construction wherein no structural change will be required in the rails 20 or fish plates at the rail joints.

A still further object of the invention is to provide an arrangement wherein the fish plates at each rail joint will be supported at their ends by ties and wherein a tie will 25 also be disposed immediately beneath the meeting ends of the rails.

And the invention has as a still further object to provide a construction wherein the joint supporting ties will be sustained beneath the rail joints by sleepers disposed to 30 extend longitudinally of the track rails projecting at opposite sides of each of the joints.

Other and incidental objects will appear as the description proceeds. In the drawings, wherein I have illustrated the preferred embodiment of the invention, and 35 wherein similar reference characters designate corresponding parts throughout the several views:

40 Figure 1 is a perspective view showing a portion of a railway track constructed in accordance with the present invention, and

Fig. 2 is a fragmentary side elevation more particularly illustrating the disposition 45 of the joint supporting ties and the sustaining sleeper beneath the adjacent ends thereof.

In carrying the invention into effect I employ parallel track rails 10 and 11. Each 50 of these rails is formed with suitable joints and in the drawings I have shown a typical rail joint wherein the rails at their meeting ends are connected by fish plates 12 secured by bolts or other suitable fastening devices 55 13 in the customary manner. Supporting the rails are spaced parallel cross ties 14 of

wood or other approved material. At each of the rail joints I employ a set of joint supporting ties 15, 16 and 17 respectively, three such ties being shown in connection with the 60 typical rail joint illustrated. These ties are similar to the ties 14 and, as will now be observed upon particular reference to Fig. 2 of the drawings, the ties 15 and 16 are disposed beneath the ends of the fish plates 65 12 of the joint while the tie 17 is disposed immediately beneath the meeting ends of the rails intermediate of the ends of the fish plates. This disposition of the joint supporting ties is preferably preserved at each 70 of the rail joints of the track and in employing the invention in different track constructions wherein the fish plates vary in length; the ties 15 and 16 may be arranged either farther apart or closer together in 75 order to lie beneath the ends of the fish plates at each of the rail joints while the tie 17 will be disposed between the ties 15 and 16, as illustrated in the drawings, immediately beneath the meeting ends of the rails. 80 Sunk into the track bed at each of the rail joints is a sleeper 18. This sleeper may be formed of an ordinary cross tie or may be specially constructed to be either longer or shorter than an ordinary tie. As will be 85 inferred from the foregoing, the sleepers may be formed of wood, cement or other approved material and, as illustrated in connection with the typical sleeper 18 shown, are arranged at the rail joints to extend 90 longitudinally of the track rails in the planes thereof sustaining the adjacent end portions of each set of joint supporting ties. The length of the sleepers may be varied, of course, in order to obtain the best results, 95 but, as shown in connection with the sleeper 18, are preferably of a length to extend at opposite sides of each set of joint supporting ties beneath adjacent cross ties 14 of the track for thus also supporting such of said 100 cross ties and consequently rigidly sustaining the end portions of the rails for some distance at each side of each of the rail joints.

As will now be seen in view of the preceding description, the sleepers 18 will rigidly sustain the sets of joint supporting ties at the end portions thereof lying beneath the rail joints. Consequently, the ties 15 and 16, as shown in connection with 110 the set illustrated, will rigidly support the fish plates 12 at the ends thereof while the

tie 17 will rigidly support the fish plates intermediate of their ends and will also support the rails directly beneath their meeting ends. Sagging of the rails at the joints therebetween will thus be prevented and relative vertical movement of the rail ends overcome so that breaking of the rails from this cause will be eliminated. Furthermore, since the end portions of the rails will be rigidly sustained by the sleepers and adjacent cross ties of the track at opposite sides of each of the rail joints, any tendency of the rolling stock to excessively pound the rails immediately at each side of the rigidly supported joints will also be overcome.

Having thus described the invention, what is claimed as new is:

In railway track construction including parallel track rails each having joints, and

spaced cross ties supporting the rails between the joints, the combination of a set of joint supporting ties bunched at each of the joints and including a tie disposed beneath the meeting ends of adjacent rails, and ties disposed at opposite sides of the first tie and lying close thereto, and sleepers extending longitudinally of the rails beneath adjacent ends of the joint supporting ties of said sets and centered with respect thereto at the rail joints for supporting said ends of the ties of the sets adjacent the joints, the sleepers being independent of said sets of joint supporting ties and terminating beyond the cross ties of the track lying immediately at opposite sides of the sets of joint supporting ties.

In testimony whereof I affix my signature.

JOHN M. WHEELER. [L.S.]
